UNITED STATES PATENT OFFICE

2,006,302

MARKING MACHINE

Charles F. Robbins, Keene, N. H., assignor to
Markem Machine Company, Keene, N. H., a
corporation of New Hampshire

Application November 28, 1933, Serial No. 700,063

5 Claims. (Cl. 101—348)

This invention relates to printing machines or marking machines of that class in which the ink is applied to the type characters of the printing head through the medium of an ink roll.

5 In the operation of a printing machine of this type the continual rolling of the ink roll across the type characters for inking the latter is apt to cause some portions of the surface of the ink roll to become matted down or compressed
10 thus giving the roll an uneven surface.

One of the objects of the present invention is to provide novel means by which the used ink rolls for marking machines can be conditioned and the surface thereof brought back to substantially its original condition.

In the drawings:

Fig. 1 is a side view of a marking machine having my improved ink roll conditioner applied thereto;

20 Fig. 2 is a section on the line 2—2, Fig. 1;

Fig. 3 is a top plan view of Fig. 1 with a part broken out;

Fig. 4 is a section on the line 4—4, Fig. 2;

25 While the ink roll conditioner herein described is applicable for conditioning ink rolls in various marking machines yet for convenience I have shown it as used in connection with a marking machine such as is illustrated in my co-pending application, Serial No. 674,551, filed June 6, 1933, 30 of which this application is a division.

The marking machine herein illustrated is formed with a main frame 1 having the base portion 2 which carries the usual work-supporting plate 3 on which the work to be printed is supported. The printing head is indicated generally at 4 and it is provided with a plurality of adjustable type wheels 5 each carrying at its surface a plurality of type characters. The printing head is carried by a swinging arm 6 pivoted to the main frame 1 and is movable toward and from the platen as usual in printing machines of this general type.

40 The vertical movement of the printing head may be provided for in various ways. As herein shown the lever arm 6 has a toggle lever 7 connected thereto and the rising and falling movement of the printing head 4 is accomplished by the breaking and straightening toggle 7, this being done by means of a suitable eccentric carried on the driving shaft 8.

45 The type characters are inked through the operation of an inking roll 9 which is mounted in a carriage 10 that slides back and forth in ways 11 that are formed on the arm 6, this being 50 the construction illustrated in said co-pending

application, Serial No. 674,551. The inking roll receives its ink from an inking plate 12 over which it rolls during the last part of its rearward stroke which occurs when the printing head is in its lowered or printing position. When the printing head is raised the carriage 10 is moved forwardly along the ways 11 to carry the inking roll underneath and across the type characters thereby inking the latter. This movement of the carriage is secured through the medium of a suitable eccentric or cam (not shown) on the shaft 8, as illustrated in my said co-pending application. The shaft 8 is driven from the driving pulley 14 through suitable driving connections which include a clutch.

55 The inking rolls 9 which are used in printing machines of this type usually have a felt surface which absorbs ink as the roll is rolled over the inking plate 12. After continued use the portions of the felt surface of the ink roll which engage the type characters for inking the latter frequently gets matted down or compressed so that when the ink roll is rolled over the inking plate 12 such matted-down or compressed portions are not properly inked, with the result that the ink roll will not function properly.

20 The object of the present invention is to provide means for conditioning worn ink rolls so as to bring them back again into a suitable condition for use. This conditioning operation is accomplished by subjecting the used or worn ink roll to the action of ironing rolls which serve to level up the surface of a worn ink roll and also serve to thoroughly distribute ink over the surface thereof. The conditioning device is in the form 25 of an attachment secured to the printing machine and operated from the driving pulley 14 or some other suitable moving part of the machine. This conditioning attachment comprises a housing 16 which is secured to the side of the machine by suitable clamping bolts 17, said bolts extending through arms or lugs 18 with which the housing 16 is provided. Mounted in the housing 16 is a positively-driven conditioning roll 19 30 preferably having a metallic surface, and a co-operating conditioning roll 20, between which rolls the ink rolls 9 to be conditioned may be placed.

35 The lower conditioning roll 19 is shown as fast on a shaft 21 journaled in bearings 22 with which the housing 16 is provided and said shaft 21 has a pulley 23 thereon which is connected by a belt 24 with a pulley 25 fast on a countershaft 26 that is journaled in bearings 27 mounted on the housing 16. The countershaft 26 has a pulley 28 thereon 40

which is connected by a belt 29 to a pulley 30 that is rigid with the driving pulley 14. With this construction the conditioning roll 19 will be positively and continuously driven from the driving pulley 14.

The housing 16 is provided with two upstanding ribs 31 that are formed with slots or notches 32 to receive the trunnions 33 of the ink rolls 9 to be conditioned, and when the trunnions 33 of the ink rolls are resting in the notches 32 the ink rolls will rest on the positively-driven conditioning roll 19.

The housing 16 is shown as provided with a cover or door 34 which is pivoted to the housing 15 at 35 and which may be swung upwardly about its pivot 35 to give access to the housing, said cover having the handle 36 for convenience in manipulating it. The upper conditioning roll 20 is shown as rotatively mounted in the door or cover 20 34. For this purpose said door or cover is formed with two depending flanges 37 and the roll 20 is provided with a spindle or shaft 38 which is journaled in these flanges 37.

Means are provided for giving the roll 20 a reciprocating movement in the direction of its length so that during the conditioning operation the ink rolls will have a rolling contact with the positively-driven roll 19 while the upper conditioning roll 20 will be moved back and forth in the direction of the length of the ink rolls and thus produce a rubbing and ironing effect. While any suitable means for giving the upper conditioning roll 20 its reciprocating movement may be employed, a simple means is herein illustrated. 35. The shaft or spindle 38 of the upper roll 20 extends beyond the outer flange 37 of the cover 34 and has a grooved pulley 39 thereon. The shaft 21 of the lower conditioning roll 19 has fast thereon a disk 40 which is set at an angle to the axis of the shaft so that as the shaft rotates said disk will have a wobbling motion. When the cover 34 is closed the upper edge of this disk is received in the groove of the pulley 39 and as the shaft 21 is rotated the wobbling motion of the disk 40 produces a reciprocating motion of the shaft 38 in the direction of its length and also tends to rotate the pulley 39 and the roll 20.

41, 41 indicates two centering springs which encircle a shaft or spindle 38 on each side of the roll 20, each spring being confined between the roll and a supporting flange 37. As the roll 20 is reciprocated between the full and the dotted line positions Fig. 2 by the wobbling motion of the disk 40 the springs 41 are alternately compressed.

It will be noted that the upper conditioning roll 20 is carried in the cover 34. When the cover is in closed position with the upper conditioning roll 20 resting on the ink rolls 9 the weight of the cover 32 on the upper conditioning roll 20 is received by the ink rolls and, therefore, this weight constitutes means for pressing the upper conditioning roll against the ink rolls. Such pressure together with the action of the two conditioning rolls serves to give the ink rolls a smooth even surface.

The ribs 31 of the housing are shown as provided with notches 42 in which spare or extra inking rolls may be placed. This device, therefore, serves not only as a conditioning device for conditioning the rolls but also as a receptacle for spare ink rolls.

It is possible also to use this device as means for inking the rolls. If, for instance, a small quantity of ink is placed on either of the con-

ditioning rolls the co-operation of said rolls with the inking roll will serve to distribute this ink thoroughly onto the inking roll.

The conditioning roll 19 has a rolling contact with the inking rolls 9 while the upper conditioning roll 20 has a rubbing contact with the ink rolls in the direction of their length and this combined action serves not only to smooth out and condition the ink rolls but also to distribute the ink evenly over the surface of the ink rolls.

43 indicates a spring latch having a notch 44 adapted to engage a pin 45 on the cover 34 when the latter is opened, said latch serving thus to hold the cover in its raised or open position. The latch 43 is acted on by a spring 46 which yieldingly holds it in engagement with the pin 45.

I claim:

1. An ink roll conditioning attachment for printing machines comprising a fixed supporting member, a conditioning roll rotatably mounted therein, said supporting member having means for supporting an ink roll of a printing machine in a position resting on the conditioning roll, said means permitting ready removal and replacement of the ink roll, a second conditioning roll, and means supporting the same in position to rest on the ink roll, said means providing for separation of the second conditioning roll from the ink roll to permit the latter to be removed from the supporting member or to be replaced therein, means for rotating one of the conditioning rolls, and means for reciprocating the other conditioning roll in the direction of the length of the ink roll.

2. An ink roll conditioning attachment for printing machines comprising a fixed supporting member, a conditioning roll rotatably mounted therein, said supporting member having means for supporting an ink roll of a printing machine in a position resting on the conditioning roll, said means permitting ready removal and replacement of the ink roll, a member pivotally connected to the supporting member, a second conditioning roll carried thereby and adapted to rest on the ink roll, and means to rotate one of the conditioning rolls and to reciprocate the other roll in the direction of the length of the ink roll.

3. An ink roll conditioning attachment for printing machines comprising a housing, a conditioning roll journaled therein, said housing having means for supporting an ink roll of a printing machine in a position resting on the conditioning roll and permitting said ink roll to be removed or replaced, a cover member pivoted to the housing, a second conditioning roll journaled in the cover and adapted to rest on the ink roll, means for positively rotating one of the conditioning rolls, and means for reciprocating the other conditioning roll in the direction of the length of the ink roll.

4. An ink roll conditioning attachment for printing machines comprising a fixed supporting member, a conditioning roll rotatably mounted therein, said supporting member having means for supporting an ink roll of a printing machine in a position resting on the conditioning roll, said means permitting ready removal and replacement of the ink roll, a second conditioning roll, means supporting the same in position to rest on the ink roll, said means providing for separation of the second conditioning roll from the ink roll to permit the latter to be removed from the supporting member or to be replaced therein, means to rotate the first-named conditioning roll, and means

actuated thereby to reciprocate the other conditioning roll in the direction of the length of the ink roll.

5. An ink roll conditioning attachment for printing machines comprising a housing, a conditioning roll journaled therein, said housing having means for supporting an ink roll of a printing machine in a position resting on the conditioning roll and permitting said ink roll to

be removed or replaced, a cover member pivoted to the housing, a second conditioning roll journaled in the cover and adapted to rest on the ink roll, means to rotate the first-named conditioning roll, and means actuated thereby to reciprocate the other conditioning roll in the direction of the length of the ink roll.

5

CHARLES F. ROBBINS.
